UNITED STATES PATENT OFFICE.

TANDY A. BRYSON, OF TROY, NEW YORK, ASSIGNOR TO TOLHURST MACHINE WORKS, A CORPORATION OF NEW YORK.

CENTRIFUGAL MACHINE.

1,331,692.

Specification of Letters Patent. Patented Feb. 24, 1920.

Application filed December 31, 1917. Serial No. 209,808.

To all whom it may concern:

Be it known that I, TANDY A. BRYSON, a citizen of the United States, residing at Troy, in the county of Rensselaer and State 5 of New York, have invented new and useful Improvements in Centrifugal Machines, of which the following is a specification.

The invention relates to centrifugal machines, and more particularly to centrifugal machines for treating galvanized or 10 dipped metal articles.

Objects of the invention are to provide a machine for rapidly and easily handling small dipped metal articles during the removal of surplus metal therefrom by centrifugal action and during the subsequent 15 delivery and cooling thereof; to avoid in such work the use of the dipping baskets within the centrifugal basket, which is slow, cumbersome and troublesome; to provide 20 for the easy and rapid discharge of the finished work directly from the centrifugal basket. Other objects of the invention will be set forth in part hereinafter and in part 25 will be obvious herefrom, or may be learned through practice with the invention.

The invention consists in the novel parts, constructions, combinations and improvements herein shown and described.

30 The accompanying drawings referred to herein and constituting a part hereof, illustrate one embodiment of the invention, and together with the description serve to explain the principles thereof.

35 Of the drawings:

Figure 1 is a vertical section, substantially on the line A—B of Fig. 2, of a centrifugal machine constructed in accordance with the principles of the invention;

40 Fig. 2 is a horizontal section on the line C—D of Fig. 1 with the basket, shaft and certain other parts omitted;

Fig. 3 is a fragmentary elevation showing an embodiment of cooling and discharge 45 mechanism for the product; and

Fig. 4 is a like showing of a discharging means for the work.

Referring now in detail to the exemplified embodiment of the accompanying drawings, 50 a centrifugal machine is illustrated having

a frame of any suitable form, and shown with uprights 1 and 2 and a top cross piece 3. In accordance with certain features of the invention, a suspended centrifugal is preferably employed, and in the embodied 55 form the basket shaft 4 is supported from the cross frame piece 3. The journal and drive 5 for the shaft 4 is mounted on the frame member 3, and is driven in a suitable manner, as by a belt 6, running over 60 pulleys 7 and over a driving pulley 8. Pulley 8 may be driven from the fast and loose pulley mechanism 9. It will be understood that any other suitable or convenient driving mechanism may be provided if 65 desired.

Suspended from the shaft 4 is a basket, indicated generally by reference numeral 15. The basket is provided with perforated cylindrical walls, the upper portion 16 70 thereof being preferably straight or vertical and the lower part thereof being preferably steeply inclined toward the bottom central portion of the basket, as shown in Fig. 1.

The basket 15 is suspended from the 75 shaft 4 in suitable manner, as by a sleeve 18 having a tapered fit on the bottom end of the shaft 4, and being held in position thereon by a nut 21. The sleeve 18 has arms or spiders 19 which extend outwardly therefrom and are connected to the lower rim 20 of the basket, to support and whirl the basket with the shaft.

The space between the arms 19 constitute 85 a bottom discharge 24 from the basket for the finished work, as is indicated by the arrows in Fig. 1. The discharge openings 24 are closed by a conical valve 25 encircling and fitting about the shaft 4. The valve 25 is slid upwardly along the shaft 4 to 90 discharge the work when the operations thereon are completed and is slid downwardly to the position shown in Fig. 1 to close the discharge openings to receive the new work. Suitable devices (not shown) 95 may be employed for so raising and lowering the valve 25 and may be attached to the sleeve of the valve surrounding shaft 4 and shown in Fig. 1 as extending above lids 37. By reason of the steeply inclined 100

portion of the basket bottom, the work will slide out through the discharge openings when valve 25 is raised without any handling on the part of an operative.

Means are provided by the invention for maintaining in the basket during the whirling thereof to throw off the surplus dipped metal a sufficiently high temperature to prevent undesirable cooling of the work, which 10 cooling would tend to retain too much of the coating metal upon the work. Coöoperating therewith are quick work loading and work discharging means, which obviate leaving the machine open except for very brief periods, 15 and thereby conserve the high temperature in the centrifugal basket.

In the embodied form of such means, heating means are provided preferably applied about the cylindrical casing 28, which 20 casing is preferably of the usual metal and surrounds the basket 15. The casing 28 is surrounded by a cylindrical wall 29 of any suitable material which is a non-conductor for heat. Extending inwardly from the wall 25 29 to the top of the casing 28 is a top closure 30 of similar non-conducting material, and a like bottom closure 31 is preferably provided.

Suitable heating means are provided, and 30 as embodied, a furnace 32 opens into the space between the casing 28 and the outer encircling wall 29. An outlet 33 conveys away the hot gases after they have passed around the casing 28, the wall 34 separating 35 the inlet and outlet for the hot gases.

The top of the casing 28 is provided with means for preventing the escape of heat from within the casing, and for this purpose there are two semi-circular closures or lids 40 37, attached by hinges 38 to the inwardly projecting top portion 36 of the casing 28. These lids 37 fit around the shaft 4, and need to be opened only when the new work is dumped into the basket, as the finished work 45 is discharged from the bottom of the basket. The top of the casing is thus practically continually closed. A trough 39, outwardly and circularly inclined, is preferably provided for flowing away the molten metal 50 thrown off from the work by the centrifugal action.

In accordance with certain features of the invention, means are provided for conveying away the finished work from the centrifugal 55 basket so as to avoid any lifting out or other troublesome and undesirable handling of the hot work. Means are also provided, if desired, coöoperating with the conveying means for cooling the finished work, so that 60 it may be easily and rapidly handled as it comes from the centrifugal machine.

In Fig. 3 of the drawings, there is shown an embodiment of cooling and conveying means. Therein, a slidable closure 45 is provided for an opening in the floor 14, the

closure working in guides 46 and 47, the closure being withdrawn to permit the downward passage of the finished work.

Beneath the closure, as embodied, is a container 48 for the water or other cooling 70 medium, having preferably inclined sides, and having an inlet 49 near the bottom and an outlet 50 near the top thereof. An endless conveyer 51 is shown running over rollers 52 and 53, the conveyer extending upwardly through an upwardly and outwardly inclined extension of the container 48. The discharged articles pass from the basket 15 through the cooling water and are deposited on conveyer 51, which conveys them away 80 and discharges them into a suitable receptacle 54.

In Fig. 4 of the drawings, a substantially horizontally arranged conveyer 55 is shown extending outwardly from beneath the discharge orifice of the centrifugal basket to the exterior side of the wall 29 and preferably to any suitable receiving device, such as the receptacle 54 shown in Fig. 3. The conveyer 55 runs over rollers 56, mounted in 90 journal blocks 57, and guide plates 58 may be used to direct the discharged work to, and to retain it upon, the conveyer.

The manner of operation and utilization of the illustrated mechanism is substantially 95 as follows:—

The usual dipping basket containing the "galvanized" or coated articles is lifted from the bath, the cover 37 is momentarily raised and the work dumped from the dipping basket into the centrifugal basket 15, the lid 37 being thereupon closed. As the basket rotates the superfluous metal is thrown from the work, and striking the casing 28 flows down into the trough or gutter 39, and flows away. When all the superfluous metal is thrown off from the work the basket 100 is stopped, the valve 25 is raised and the hot work slides out through the openings 24. There are no dipping baskets or other cumbersome devices to be placed within the centrifugal basket 15, the interior of which 105 is always clear except for the work being operated upon, and when the work is finished there is no handling of the hot work, nor 110 any removal of hot baskets or fixtures from the centrifugal basket 15, necessary. The manner of operation of the discharge device has already been explained. The work is 115 discharged almost instantaneously, and without any lifting of hot baskets or any lifting whatsoever, and the finished work is delivered automatically by the machine and is cool enough to be handled with comfort and safety. The machine can be reloaded in another instant after discharging and this both 120 keeps the machine steadily at work and also conserves the heat.

It will be understood that changes may be made from the precise form of mechanism 130

shown and described, without departing from the principles of the invention and without sacrificing its chief advantages.

What I claim is:—

5. 1. A centrifugal machine including in combination a whirling open top basket having a bottom closure, a fluid intercepting casing surrounding the basket and having lids closing the space above the basket and 10 having an inwardly projecting bottom fitting around the bottom part of the basket, and means for heating the space within the casing.
2. A centrifugal machine including in combination a whirling open top basket having a bottom closure, a fluid intercepting casing surrounding the basket and having lids closing the space above the basket and 15 having an inwardly projecting bottom fitting around the bottom part of the basket, and a heating chamber surrounding but not communicating with the casing.
3. A centrifugal machine including in combination a whirling open top basket having a bottom closure, a fluid intercepting casing surrounding the basket and having lids closing the space above the basket and 20 having an inwardly projecting bottom fitting around the bottom part of the basket, and inclined to drain the thrown-off molten metal to a single point, and means for heating the space within the casing.
4. A centrifugal machine including in combination a whirling perforate basket, an 25 imperforate heat conducting closure around and above and beneath the basket, a heat insulating wall about the heat conducting closure and forming therewith a heating chamber, the heat conducting chamber having a central bottom opening and the basket 30 having a bottom discharge in line with the opening, the basket substantially closing the opening in the bottom of the heat conducting chamber.
5. A centrifugal machine including in combination a whirling perforate basket, an imperforate heat conducting closure around and above and beneath the basket, a heat 35 insulating wall about the heat conducting closure and forming therewith a heating chamber, the heat conducting chamber having a central bottom opening and the basket 40 having a bottom discharge in line with the opening, the basket substantially closing the opening in the bottom of the heat conducting chamber.
6. A centrifugal machine including in combination a whirling perforate basket, a shaft supporting the basket from above and 45 a drive therefor, an imperforate heat conducting closure around and above and beneath the basket, a heat insulating wall about the heat conducting closure and forming therewith a heating chamber, the heat conducting chamber having a central bottom opening and the basket 50 having a bottom discharge in line with the opening, the basket substantially closing the opening in the bottom of the heat conducting chamber, and a conveyer extending from the bottom of the basket to the outside of the insulating wall.
7. A centrifugal machine including in combination a whirling perforate basket, an imperforate heat conducting closure around and above and beneath the basket, a heat insulating wall about the heat conducting closure and forming therewith a heating chamber, the heat conducting chamber having a central bottom opening and the basket 55 having a bottom discharge in line with the opening, the basket substantially closing the opening in the bottom of the heat conducting chamber.
8. A centrifugal machine including in combination a whirling perforate basket, a shaft supporting the basket from above and a drive therefor, an imperforate heat conducting closure around and above and beneath the basket, including a top lid, a heat insulating wall about the heat conducting closure and forming therewith a heating chamber, the heat conducting chamber having a central bottom opening and the basket 60 having a bottom discharge in line with the opening, the basket substantially closing the opening in the bottom of the heat conducting chamber.
9. A centrifugal machine including in combination a whirling perforate basket, an imperforate heat conducting closure around and above and beneath the basket, including a plurality of lids opening back from the center of the casing, a heat insulating wall about the heat conducting closure and forming therewith a heating chamber, the heat conducting chamber having a central bottom opening and the basket 65 having a bottom discharge in line with the opening, the basket substantially closing the opening in the bottom of the heat conducting chamber.
10. A centrifugal machine including in combination a whirling perforate basket, a shaft supporting the basket from above and a drive therefor, an imperforate heat conducting closure around and above and beneath the basket, including a plurality of lids opening away from the shaft, a heat insulating wall about the heat conducting closure and forming therewith a heating chamber, the heat conducting chamber having a central bottom opening and the basket 70 having a bottom discharge in line with the opening, the basket substantially closing the opening in the bottom of the heat conducting chamber.
11. A centrifugal machine including in combination a whirling perforate basket, an imperforate heat conducting closure around and above and beneath the basket, said bottom being inclined to form a hot metal 75

drain, a heat insulating wall about the heat conducting closure and forming therewith a heating chamber, the heat conducting chamber having a central bottom opening 5 and the basket having a bottom discharge in line with the opening, the basket substantially closing the opening in the bottom of the heat conducting chamber.

In testimony whereof, I have signed my name to this specification in the presence of 10 two subscribing witnesses.
